(57) **CLAIM**

The ornamental design of a wallet-mounted wireless device holder, as shown and described.

DESCRIPTION

FIG. 1 is a back, top, and right side perspective view of a wallet-mounted wireless device holder; FIG. 2 is a back, bottom, and left side perspective view thereof;

FIG. 3 is a front plan view thereof;

FIG. 4 is a back plan view thereof;

FIG. 5 is a right plan view thereof;

FIG. 6 is a left plan view thereof;

FIG. 7 is a top plan view thereof; and,

FIG. 8 is a bottom plan view thereof.

The dashed broken lines in the drawings show portions of the wallet-mounted wireless device holder that form no part of the claimed design.

1 Claim, 6 Drawing Sheets
